PRY TYPE LID LIFTER AND RETAINER

William Stephen Burnard, Winnipeg, Manitoba,
Canada

Application October 8, 1949, Serial No. 120,339

4 Claims. (Cl. 81—3.1)

1

My invention relates to new and useful improvements in can openers, particularly suitable for use upon cans having a snap lid or a lid which is receivable within an aperture formed in the upper surface of the can, an object of my invention being to provide a device of the character herewithin described which facilitates the removal of such lid without recourse to screw-drivers, knives or the like.

A further object of my invention in conjunction with the foregoing object is to provide a device of the character herewithin described by which means the lids of cans can be removed without risk of injury to the hand of the operator, a risk that is extremely prevalent when a knife or screw-driver is used in lieu thereof.

Another object of my invention is to provide a device of the character herewithin described which retains the lid firmly after removal thereby eliminating contamination of the undersurface of the lid with dirt, dust or the like.

A still further object of my invention is to provide a device of the character herewithin described which is adaptable for use with all sizes of cans using this form of snap lid.

A yet further object of my invention is to provide a device of the character herewithin described which is economical in manufacture, simple in operation, and otherwise well suited for the purpose for which it is designed.

With the foregoing objects in view, and such other objects and advantages as will become apparent to those skilled in the art to which this invention relates as this specification proceeds, my invention consists essentially in the arrangement and construction of parts all as hereinafter more particularly described, reference being had to the accompanying drawings in which:

Figure 1 is a perspective view of a can having a snap lid and showing one embodiment of my device in situ.

Figure 2 is a fragmentary cross sectional view of Figure 1 showing the engagement of my device upon the can and lid.

Figure 3 is a perspective view of an alternative embodiment of my invention.

Figure 4 is a fragmentary perspective view of yet another alternative embodiment of my device.

Figure 5 is a perspective view of another alternative embodiment of my device shown in the lid-gripping or lid-removed position.

In the drawings like characters of reference indicate corresponding parts in the different figures.

Snap lids of cans such as paint cans, syrup tins and the like normally require the use of a screw-driver or knife in order to lever same free from the lid aperture. Due to the efficient seal

2

existing between the lids and cans using this form of closure, considerable leverage is normally required in order to pry loose the lid and, if a screw-driver, knife or ice-pick for example is used for this removal, there is the danger of injury to the hand of the operator.

Furthermore, if the can contains a viscous liquid such as paint, syrup or the like, there is normally a deposit of said liquid upon the underside of the lid. When the lid is pried loose from the can usually with considerable force, the lid normally drops to the surface upon which the can is resting and, if the underside of the lid contacts the surface, there is risk of contamination of the contents of the can when the lid is replaced together with the undesirable smearing or spattering of the contents upon said surface.

Consequently I have designed the opener hereinafter to be described which, apart from removing the danger attending the prying loose of the lid, also includes means whereby the lid is held firmly within the opener after removal from the can whereupon it may be placed where desired or, if necessary, replaced upon the can without handling the lid.

Proceeding now to describe my invention in detail, it will be seen upon reference to the accompanying drawings that I have illustrated several embodiments thereof, these embodiments being shown in Figures 1, 3, 4 and 5.

The embodiment shown in Figure 1 comprises a handle 1 having a pair of lever arms 2 formed from relatively stiff wire or the like, extending from point of attachment 3 and diverging outwardly to a point substantially medially along the length thereof, indicated by the reference character 4. The lever arms 2 then continue substantially parallel to form the portions 5 upon the distal ends of which I have formed lid-lip engaging claws 6 by angulating the ends substantially at right angles to the axis of the arms, the extremities 7 of the claws being sharpened to facilitate engagement beneath the lip 8 of a lid 9 of an associated can 10.

A resilient lid retainer component 11 formed preferably from spring steel strip, extends from the portion 3 of the handle 1 substantially between the two lever arms 2 and is angulated at the extremity 12 thereof through substantially 180° to form a lid engaging finger 13. This finger is angulated in opposition to the aforementioned claws 6 and lies substantially therebetween and projects slightly beyond the plane of the claws for the purpose hereinafter to be described. Normally the resiliency of the strip causes the portion 13 to project between the claws 6 in a plane lying behind the rear surfaces 14 of the arms 2. In operation, the claws 6 are engaged beneath

the lip 8 of the lid 9, the sharpened extremities 7 assisting in this engagement. The lid retainer component 12 is sprung so that the finger 13 engages against the interior vertical surface 15 of the lid as clearly shown in Figure 2 of the accompanying drawings. The opener is now rotated in the direction of the strap arrow 16, whereupon the locus of angulation 17 of the claws 6 bears against the rim 18 of the can 10 thereby providing leverage which removes the lid from the opening 19. When rotation of the opener is completed, the claws 6 and the finger 13 co-act with the lid 9 holding same firmly as clearly illustrated in Figure 5 of the accompanying drawings thereby permitting same to be placed where desired without handling same.

Figure 3 of the accompanying drawings shows an alternative embodiment of my device comprising a handle 20 to which is adjacently formed a lever arm 21 having a lip engaging claw 22 formed upon the distal end thereof, the handle 20, the arm 21 and the claw 22 being formed of flat stock strip material having flanged sides 23 for rigidity.

A resilient lid retainer component 24 manufactured preferably from spring steel strip, engages within a pair of transverse slots 25 formed within the handle 20 and extends forwardly and under the claw 22 projecting forwardly therefrom as clearly shown in the drawing. The distal end 25' of the component 24 is rolled to facilitate engagement with the lid as described in the previous embodiment.

Figure 4 of the accompanying drawings shows a further alternative embodiment in which the lever arm 26 is formed of relatively stiff wire and angulated at the distal end thereof to form the engaging claw 27. The lid retainer component 28 is manufactured preferably from spring steel wire and curves downwardly and under the claw 27 to project slightly forwardly therefrom as clearly illustrated.

Figure 5 of the accompanying drawings shows an embodiment including a handle 29 having a lever arm 30 extending therefrom upon the distal end of which is formed the lid engaging claw 31. The resilient lid retainer component 32 extends forwardly from the handle 29 in overlapping relationship to the lever arm 30 and is provided with a lip engaging finger 33 upon the distal end thereof angulated in opposition to the aforementioned claw 31. A feature of this embodiment is the provision of means for depressing the retainer component 32 against the resiliency thereof which comprises a button 34 having a stem 35 freely engageable within an aperture in the lever arm 30, the inner end of said stem being provided with a depressor 36 which bears against the inner surface of the component 32 and facilitates the separation of the finger 33 and the claw 31 both for engagement and disengagement about the lip 8 of the lid 9. In this connection it will be noticed that the portion 37 of the lid retainer component 11 illustrated in Figure 1 normally extends between the arms 2 thereby providing what I define as a finger engaging portion by which means the retainer component can be depressed from the lever arms.

Since various modifications can be made in my invention as hereinabove described, and many apparently widely different embodiments of same made within the spirit and scope of the claims without departing from such spirit and scope, it is intended that all matter contained in

15 the accompanying specification shall be interpreted as illustrative only and not in a limiting sense.

What I claim as my invention is:

- 5 1. An opener for snap-lid cans, canisters and the like, comprising in combination with a handle, a lever arm extending from said handle, a lid-lip engaging claw angulated from the distal end of said arm and a resilient lid retainer component also extending from said handle co-acting with said claw to retain the lid of said can when removed therefrom, said lid retainer component being angulated at the distal end thereof in opposition to said claw, said distal end of said retainer component being in overlapping relationship with said claw.
- 20 2. An opener for snap-lid cans, canisters and the like, comprising in combination with a handle, a pair of lever arms extending from said handle, said lever arms being angulated upon the distal ends thereof to form lid-lip engaging claws, said claws being in parallel spaced relationship one with the other, a resilient lid retainer component extending from said handle between said lever arms, a finger engaging portion formed upon said retainer component for moving same out of alignment with said lever arms, a lid engaging finger formed upon the end of said component in opposition to said claws, said finger coacting with said claws to retain the lid of said can when removed therefrom.
- 25 3. An opener for snap-lid cans, canisters and the like, comprising in combination with a handle, a lever arm extending from said handle, a lid-lip engaging claw angulated from the distal end of said arm and a resilient lid retainer component also extending from said handle co-acting with said claw to retain the lid of said can when removed therefrom, said lid retainer component being angulated at the distal end thereof in opposition to said claw, said distal end of said retainer component being in overlapping relationship with said claw, and means for depressing said retainer component away from said lever arm for engaging and disengaging the lip of said lid.
- 30 4. An opener for snap-lid cans, canisters and the like, comprising in combination with a handle, a lever arm strip extending from said handle, a lid-lip engaging claw angulated from the distal end of said strip and a resilient lid retainer component also extending from said handle co-acting with said lever arm to retain the lid of said can when removed therefrom, said retainer component being angulated in opposition to said claw to form a lid engaging finger, and means for depressing said retainer component away from said lever arm for engaging and disengaging the lip of said lid, said means comprising a button, freely engageable within said lever arm, the lower end of said button bearing against said lid retainer.

WILLIAM STEPHEN BURNARD.
